Primary Examiner — Katrina A Betton(74) *Attorney, Agent, or Firm* — SALIWANCHIK, LLOYD & EISENSCHENK(57) **CLAIM**

The ornamental design for a utility trailer floor panel, as shown and described.

DESCRIPTION

FIG. 1 is a front, left side, perspective view of a utility trailer floor panel, showing my new design;

FIG. 2 is a side elevation view thereof, with the opposite side being a mirror image;

FIG. 3 is an end elevation view thereof, with the opposite end being a mirror image;

FIG. 4 is a top plan view thereof;

FIG. 5 is a bottom plan view thereof;

FIG. 6 is an exploded view thereof; and,

FIG. 7 is a front, left side, perspective view of three panels that are connected to depict a portion of the utility trailer floor. The trailer side panel is partially cut-away to show a left end perspective view of the connected panels.

Throughout the Figures, the dashed broken lines represent environmental matter and/or unclaimed portions that form no part of the claimed design. The wavy broken lines on the trailer sidewalls indicate that the sidewalls can be longer than shown.
